UNITED STATES PATENT OFFICE.

AUGUST HOLSTE, OF BIELEFELD, GERMANY.

SHIRT WITH REMOVABLE BOSOM.

1,399,255.

Specification of Letters Patent.

Patented Dec. 6, 1921.

Application filed August 16, 1913. Serial No. 785,135.

(GRANTED UNDER THE PROVISIONS OF THE ACT OF MARCH 3, 1921, 41 STAT. L., 1313.)

To all whom it may concern:

Be it known that I, AUGUST HOLSTE, a subject of the King of Prussia, German Emperor, residing at Bielefeld, in the Kingdom of Prussia, German Empire, have invented certain new and useful Improvements in a Shirt with Removable Bosom, of which the following is a specification.

10 Shirts with breast openings for a detachable bosom which opening gradually merges into the opening for the neck present the inconvenience that the skin of the neck is easily scratched by the sharp edges and corners of the bosom, owing to the fact that the front part of the neck band is suppressed. This invention has for its purpose to obviate this inconvenience by making the ends of the neck band project over the edge of the breast opening.

20 The invention has further for its purpose to improve the fit of the detachable bosom by means of tabs arranged at either side of the neck opening and forming extensions of the front edges of the neck band.

25 In the accompanying drawings the invention is shown by way of example.

Figure 1 is a front elevation of the improved shirt.

30 Fig. 2 is a perspective view showing part of the bosom in position for being inserted.

The shirt *a* has a breast opening *b* for the bosom *c*. The edges of the breast opening cover the edges of the bosom when the same is inserted. The neck band *d* is arranged at 35 the rear part of the neck opening *e* and open at the front part so that the breast opening merges into the neck opening. On the inner surface of the shirt, near the front ends of the neck band *d* tabs *h* are arranged at the right and left of the breast opening 40 which form pockets designed to receive the upper edges *i* of the bosom, said corners of the bosom being retained between the parts *h* of the shirt and overlying the tabs *h*. The 45 tabs *h* are sewn to the shirt either along the

inner edge *l* and along the outer edge *m* (Fig. 2) in which case they form a pocket open at the bottom end only, or they are sewn only along the edge *l* in which case they form a pocket open at the inner and 50 outer ends. The edge of the part *k* of the shirt stands slightly back from the inner edge *o* of the corresponding tab *h* so that the opening of the pocket into which the edge of the bosom is to be inserted is 55 rather large.

The tabs *h* serve for maintaining the bosom in proper position and for protecting the skin against injury by the sharp edges of the bosom.

I claim:—

A shirt comprising a body provided with an open opening in its front and having a neck band extending inwardly beyond the edges of said opening, relatively small substantially rectangular interior flaps arranged at opposite sides of the front opening and fitted to the under side of the body and stitched at the neck band and at the outer edges, the inner portions of the flaps 65 being extended into said opening and connected to the inwardly projecting ends of the neck band, the lower edges of the flaps being unconnected with the shirt, said flaps coöperating with the shirt front to form 70 relatively small pockets at the upper front portions of the shirt and a removable bosom provided with a neck band and having its upper corners adjacent the neck band 75 removably fitted in the pockets which have the outer stitched edges of the flaps arranged substantially contiguous to the removable bosom.

In witness whereof I have hereunto set my hand in the presence of two witnesses. 85

AUGUST HOLSTE.
